UNITED STATES PATENT OFFICE.

WINFIELD P. PEMBROKE, OF ROCHESTER, NEW YORK.

CARBURETER.

1,241,013.

Specification of Letters Patent. Patented Sept. 25, 1917.

Application filed April 13, 1914. Serial No. 831,362.

To all whom it may concern:

Be it known that I, WINFIELD P. PEMBROKE, of Rochester, in the county of Monroe and State of New York, have invented 5 certain new and useful Improvements in Carbureters; and I do hereby declare the following to be a full, clear, and exact description of the same, reference being had to the accompanying drawings, forming a 10 part of this specification, and to the reference-numerals marked thereon.

My present invention relates to explosive engines, and more particularly to charge-forming devices therefor, and it has for its 15 object to provide a carbureter of simple and efficient construction, and embodying a charge-forming mechanism having improved means for regulating the amount of air admitted to the carbureting chamber 20 when the latter is opened to the vacuum. A further object of the invention is to embody such features to advantage in the auxiliary charge-forming device of a duplex carbureter wherein the additional fuel supply is 25 automatically brought into use only when the engine is running at the higher speeds, to the end that the secondary supply of hydro-carbon may be caused to flow and be drawn upon only with a simultaneous ad- 30mittance of air in sufficient quantity and under proper conditions to mix therewith and create a correct explosive charge. To these and other ends the invention consists 35 of certain improvements and combinations of parts all as will be hereinafter more fully described, the novel features being pointed out in the claim at the end of the specification.

In the drawings:

40 Figure 1 is a vertical section of a carbureter constructed in accordance with and illustrating one embodiment of my invention;

Fig. 2 is a horizontal detail section taken 45 substantially on the line 2—2 of Fig. 1.

Similar reference numerals in the several views indicate the same parts.

As before indicated, features of my invention are applicable to simple carbureters 50 containing only a single charge-forming element, but the improvements are best suited to carbureters embodying a main charge-forming element or primary carbureter and an auxiliary charge-forming element or 55 auxiliary carbureter that is called into play only when the demands of the engine are

greater than the primary carbureter is able to supply, in which case the feature of my invention resides in the particular construction of the auxiliary carbureter, as combined with the primary carbureter, as will hereinafter appear. Such a carbureter is illustrated herein, and referring more particularly to the drawings, 1 indicates generally the casing, 2 the vacuum chamber 60 and 3 the throttle valve or butterfly. The usual gasoline float chamber (not shown) is employed, and leading therefrom is the fuel conduit 5, having a lateral 6 through which the gasoline flows to the primary 65 fuel jet 7. The normal level maintained by the gasoline is approximately that of the top and mouth of this primary jet 7.

The main charge-forming device comprises this jet 7 and an adjacent air intake 75 8 delivering past the same and through the mixing tube 9 to the vacuum chamber 2. This source of supply is the one first drawn upon by the cylinders and is adequate for the lower speeds.

The auxiliary charge-forming device is carried on an extension of the casing 1 and vacuum chamber 2 indicated at 10, and embodies an auxiliary carbureting chamber 11, having main or stationary walls 12 and 80 open at the bottom to the atmosphere, while at the top it opens through a port 13 into the vacuum chamber 2.

A fuel jet 14 also fed from the lateral 6 projects upwardly through the lower end 90 of the chamber to the interior thereof, its top or mouth being preferably considerably higher than that of the main jet 7 so that the gasoline level is normally quite a little below it.

The port 13, between the auxiliary carbureting chamber 11 and the vacuum chamber 2, is normally closed by a valve 15, having a stem 16 guided in a plate 17 at the top of the vacuum chamber. A spring 18 coiled about the stem 16 abuts at one end against the valve head to hold it against its seat, while the other end of the spring bears against the end of a sleeve 19 threaded in the plate 17 and constituting a means for 95 adjusting the tension thereof. A sleeve 20 on the valve 15 surrounds the auxiliary carbureting chamber 11 and the central jet 14, being guided by the walls 12 and provided with ports 21 which set up communication 100 between the two chambers when the valve is raised. This sleeve 20 forms, in effect, a con-

tinuation of the walls 12, and it is through the lower end of this sleeve that the air is actually admitted from the atmosphere. The chamber 11 is normally under atmospheric pressure, which holds down the liquid fuel in the jet 14 far below the mouth thereof, at the point previously stated, and no mechanical closure for the jet is therefore required. This is by reason of the fact that a regulating cap 22, threaded upon the base of the jet 14, to permit raising and lowering adjustments, and between which and the rim of the sleeve 20, the inrushing air is admitted, is maintained in spaced relation with said sleeve even when the valve 15 is upon its seat. Such normal positions of the parts are shown in Fig. 3.

In operation, when the demand of the engine for fuel has created a greater vacuum 20 in the chamber 2 than the main charge-forming device delivering through the tube 9 can replenish to the extent required to supply the cylinders, the atmospheric pressure in the auxiliary mixing chamber 11 25 raises the valve 15 against the tension of the spring 18, which latter has been previously adjusted to offer resistance up to the proper point, and atmospheric air rushes in at the bottom of the chamber between the regulating cap 22 and the rim of the sleeve 20. The sleeve 20, being carried by the valve 15, rises at the same time and separates from the cap 22, constantly increasing the opening for the air in proportion to the 30 drain upon the auxiliary carbureting chamber 11 exerted by the vacuum in the chamber 2 which raises the valve 15 according to its own requirements. Thus if there is only a slight demand for the auxiliary mixture, 35 and the valve 15 consequently opens but very little, or to an insufficient extent to draw enough air past the jet 14 to make a really serviceable mixture, the rarification in the auxiliary carbureting chamber 11 will not be sufficient to cause such a rise of the fuel in 40 the jet as to make it discharge, as the air opening, normally maintained at the bottom, will keep up the atmospheric pressure. Immediately thereafter, however, when the 45 valve 15 rises to a considerable degree, the vacuum in the chamber 2 is immediately

communicated to the auxiliary carbureting chamber 11 and the instantaneous feed of fuel drawn from the jet 14 will be taken up by and mixed with the correspondingly increased volume of air admitted through the enlarged inlet opening at the bottom of the chamber. Therefore, the auxiliary carburetor, when feeding at all, will feed a properly constituted charge, and there will be no indecisive fluttering of the valve 15 and flooding from the jet 14 when that marginal point in the operation is reached where the full capacity of the primary mixer has been called into play and the contribution from the auxiliary carburetor is about to be drawn upon.

The threaded engagement of the regulating cap 22 on the stem 14 admits of its being adjusted toward and from the sleeve 20, with a corresponding change in the size both of the normal air inlet opening maintained to keep the chamber 11 at atmospheric pressure, and the enlarged opening that is automatically increased to give the proper 75 quantity of fuel mixing air for the delivery from the jet. A spring 23 provides a tension that holds the cap 22 in the position to which it is adjusted.

I claim as my invention: 80
In a carburetor for explosive engines, the combination with a vacuum chamber and a carbureting chamber having a port opening to the vacuum chamber at one end and an air intake opening to the atmosphere at the 85 other end, of a fuel jet projecting longitudinally into the carbureting chamber from the air inlet end thereof, a valve normally closing the port and adapted to be unseated by atmospheric pressure in the carbureting 90 chamber, a sleeve on the valve surrounding the jet and arranged to enlarge the air intake opening when unseated and a regulating cap threaded on the fuel jet to be adjusted relatively to the sleeve and co-operating therewith to vary the minimum capacity of the inlet opening. 95

WINFIELD P. PEMBROKE.
